CLAIM

The ornamental design for a casserole dish cover or the like, substantially as shown and described.

DESCRIPTION

FIG. 1 is a top perspective view of a casserole dish cover or the like showing our new design;

FIG. 2 is a bottom perspective view thereof;

FIG. 3 is a side elevational view thereof, the opposite side being identical thereto;

FIG. 4 is an end elevational view thereof; the opposite end being identical thereto;

FIG. 5 is a top plan view thereof;

FIG. 6 is a bottom plan view thereof;

FIG. 7 is a cross-sectional view taken along line 7—7 of FIG. 5.
